UNITED STATES PATENT OFFICE

2,056,073

GRATING STRUCTURE

Raymond P. Pennoyer, Pittsburgh, Pa.

Application February 6, 1934, Serial No. 710,025

6 Claims. (Cl. 189—82)

This invention relates to a grating structure, and more particularly those such as are used for reinforcing flooring for bridges, and the like.

In structures of this type, the grating is usually made of metal, and is filled with concrete, or other material. In the past, the steel grating structure has generally been used only for comparatively low stresses, while the filling material, or concrete, has been stressed to the limit 10 of its value, thereby making an inefficient combination.

Among the objects of the present invention is the provision of a novel grating structure which will increase the efficiency of the steel of the 15 grating by stressing it higher than heretofore possible, and one which will, at the same time, make possible lower stresses in the concrete, or other filling material.

These and further objects will be apparent 20 after referring to the drawing, in which:

Figure 1 is a plan of the device of the invention.

Figure 2 is a sectional view on the line II—II of 25 Figure 1.

Figure 3 is a sectional view on the line III—III 30 of Figure 1.

Referring more particularly to the drawing, the base members of grating structures of the type described are usually referred to as "girders", and in the present instance are in the form of 35 inverted T's having webs 2 and flanges 3. A plurality of inverted T's are assembled in parallel relationship, and each provided on its upper edge with a plurality of slots 4, which are curved, inclined, or otherwise deformed in cross-section. 40 The slots 4 of adjacent webs 2 are in exact transverse alignment with respect to the longitudinal axes of the girders.

A plurality of transverse bars 6 are each provided with curved portions, or nibs, 7, at spaced 45 intervals, for seating in the various slots 4 in the girders. The webs of the transverse bars 6 are of such width that when seated in the slots 4 they extend substantially upwardly from the edges of the girders. The transverse bars 6 are 50 intended to support a plurality of cross-bars which are securely attached thereto, preferably by interlocking. Accordingly, the upper edges of the transverse bars 6 are provided with a plurality of curved, or inclined, slots 8.

The cross-bars, which are indicated at 9, are each provided on their lower edges with spaced 55 nibs 10 which conform substantially to the cross-section of the slots 8, and are adapted to seat in the same in such manner as to permit their uppermost edges to lie in the same horizontal plane as those of the transverse bars 6.

While I have shown and described one specific embodiment of my invention, it will be understood that I do not wish to be limited exactly thereto, since various modifications may be made without departing from the scope of my invention, as defined in the following claims. 5

I claim:

1. A grating structure comprising a plurality of longitudinal girder bars having slots formed in their upper edges, transverse bars seated in said slots and extending vertically out of the same, said transverse bars having slots formed in their upper edges, and cross-bars seated in said last named slots.

2. A grating structure comprising a plurality of longitudinal girder bars having slots formed in their upper edges, transverse bars seated in said slots and extending vertically out of the same, said transverse bars having slots formed in their upper edges, and cross-bars seated in said last named slots, the upper edges of said cross-bars being in substantially the same longitudinal plane as those of said transverse bars. 15

3. A grating structure comprising a plurality of longitudinal girder bars having inclined slots formed in their upper edges, transverse bars having inclined nibs for seating in said slots, said transverse bars extending vertically out of said slots and having inclined slots formed in their upper edges, and cross-bars having inclined nibs 20 for seating in said last named slots. 25

4. A grating structure comprising a plurality of longitudinal girder bars having inclined slots formed in their upper edges, transverse bars having inclined nibs for seating in said slots, said transverse bars extending vertically out of said slots and having inclined slots formed in their upper edges, and cross-bars having inclined nibs 30 for seating in said last named slots, the upper edges of said cross-bars being in substantially the same horizontal plane as those of said transverse bars. 35

5. A grating structure comprising a plurality of longitudinal girder bars having slots formed in their upper edges, transverse bars seated in said slots and extending vertically out of the same, and cross-bars supported by said transverse bars. 45

6. A grating structure comprising a plurality of longitudinal girder bars having slots formed in their upper edges, transverse bars seated in said slots and extending vertically out of the same, and cross-bars supported by said transverse bars and adapted to have their upper edges lie in substantially the same horizontal plane as those of 50 said transverse bars. 55

RAYMOND P. PENNOYER.
